UNITED STATES PATENT OFFICE.

HENRY H. NIGHTINGALE, OF MOUNDRIDGE, KANSAS.

SPEED-GOVERNOR.

SPECIFICATION forming part of Letters Patent No. 715,845, dated December 16, 1902.

Application filed March 13, 1901. Serial No. 50,998. (No model.)

To all whom it may concern:

Be it known that I, HENRY H. NIGHTINGALE, a citizen of the United States, residing at Moundridge, in the county of McPherson, 5 State of Kansas, have invented certain new and useful Improvements in Speed-Governors; and I do hereby declare the following to be a full, clear, and exact description of the invention, such as will enable others skilled 10 in the art to which it appertains to make and use the same.

This invention relates to speed-governors; and it has for its object to provide a centrifugal brake mechanism wherein the brake will be 15 applied when the speed exceeds a given point, a further object of the invention being to provide means for adjusting the mechanism to respond to different speeds.

In the drawings forming a portion of this 20 specification and in which like numerals of reference indicate similar parts in the several views, Figure 1 is a sectional view taken through the fly-wheel, the brake-drum, and the brake-shoes. Fig. 2 is an elevation showing the side of the fly-wheel having the brake-shoes thereon, the position of the brake-drum being indicated in dotted lines. Fig. 3 is a 25 reverse detailed perspective view of one of the levers with the brake-shoes thereon.

Referring now to the drawings, 5 represents a shaft which is mounted so as to be held from rotating, and on this shaft is rotatably disposed a fly-wheel 6, adjacent to which and fixed to the shaft is a brake-drum 7, supported upon a disk-shaped web 8, and which drum projects over the face of the disk adjacent to the fly-wheel. The drum is adapted for frictional engagement by brake-shoes which are carried by the fly-wheel and which are 35 brought into frictional contact with the inner and outer faces of the brake-drum when the fly-wheel has acquired a predetermined speed. The brake-shoes are in the present instance four in number and include two pairs of shoes 40 9 and 10 and 11 and 12, the shoes of each pair being disposed adjacent to the inner and outer faces of the brake-drum, respectively. The mountings of the two pairs of shoes are the same, so that a description of one will 45 suffice for the other. Referring then to the shoes 9 and 10, it will be noted that their ad-

jacent faces are arcuate, the face of the outer shoe 9 being concave, while the face of the inner shoe is convex, so that they conform to the curvature of the brake-drum. These 55 shoes are mounted upon a plate 13, carried by a lever 14, pivoted upon a broadened spoke 15 of the fly-wheel, the axis of the pivot passing midway between the adjacent faces of the shoes, and the lever is held normally 60 and yieldably in position with the pivots of the shoes 9 and 10 in a common line with the axis of the fly-wheel, so that the clutching-faces of the shoes will be spaced slightly from the adjacent faces of the brake-drum. 65 If then the lever be moved, with its free end, outwardly so as to tilt the plate 13, the block-shoes 9 and 10 will be moved into contact with the adjacent faces of the drum, and because of their pivotal mounting will conform to the 70 curvature of the drum and will be forced tightly thereagainst to have a brake action.

The means for holding the lever yieldably in position to hold the brake-shoes out of contact with the drum is a helical spring 15^a, which 75 is connected with the lever and with the hub of the fly-wheel, and upon the free end of the lever beyond this helical spring there is a slidably-mounted weight 16. With the two sets of brake-shoes the brake-drum will be 80 engaged at diametrically opposite points, and it will be understood that if the fly-wheel be rotated the weights 16 will be moved outwardly of the wheel by centrifugal action and the brake will thus be applied. When 85 the speed of rotation decreases, the centrifugal force will of course decrease, and the helical springs will draw the levers inwardly to reduce the pressure of the brake-shoes upon the brake-drum. By shifting the weights 90 along the levers the centrifugal force applied through levers through the brake-shoes may of course be adjusted, the shifting of the weights having the effect of varying the length of the levers. To limit the inward 95 movement of the levers, so that the brake-shoes will not be reversely applied, stops 17 are formed upon the hub of the fly-wheel.

In practice the fly-wheel may be connected with the engine to be governed by means of 100 a belt, or, if preferred, the shaft shown may be rotatable and form the crank-shaft of the en-

gine, the brake-drum being fixed against rotation, while permitting the shaft to turn freely therein.

Other modifications of the specific construction shown may be made, and any suitable materials and proportions may be used for the various parts without departing from the spirit of the invention.

What is claimed is—

10. The combination, with a fixed brake-drum, of a rotatable fly-wheel adjacent to the drum, a plate pivoted on the fly-wheel and projecting above and below the edge of the drum, brake-shoes pivoted upon the ends of the
15. plate, and disposed for engagement with the inner and outer sides of the drum, a lever, a

shiftable weight upon said lever adapted to be moved by centrifugal force to apply the shoes to the brake-drum, means for holding the plate yieldably with the pivots of the 20 shoes in the plane of the axis of the wheel to hold the shoes out of operative relation to the brake-drum, and means to limit the movement of the lever toward the axis of the wheel.

In testimony whereof I hereunto sign my name, in the presence of two subscribing witnesses, on the 28th day of February, 1901.

HENRY H. NIGHTINGALE.
